UNITED STATES PATENT OFFICE

101,630

DESIGN FOR A GLASS ASHTRAY OR SIMILAR ARTICLE

T. Clarence Heisey, Newark, Ohio

Application March 6, 1936, Serial No. 61,508

Term of patent 3½ years

To all whom it may concern:

Be it known that I, T. Clarence Heisey, a citizen of the United States of America, residing at Newark, in the county of Licking and State of Ohio, have invented a new, original, and ornamental Design for a Glass Ashtray or Similar Article, of which the following is a specification, reference being had to the accompanying drawing, forming a part thereof.

Figure 1 is a perspective view of a glass ashtray showing my new design.

Figure 2 is a bottom plan view of the article shown in Figure 1.

Figure 3 is a section taken substantially along line 3—3 of Figure 2.

My design consists of a glass ashtray having

substantially the following features: side walls having vertically extending alternate ridges and notches on their outer surfaces, and a bottom having alternate ridges and grooves formed on the lower surface thereof, all of which converge at the center, the ridges coming substantially to a point at the center and becoming wider towards the side walls of the article, the outer ends of the ridges and grooves on the bottom being in alignment with the corresponding ridges and notches on the side walls of the article.

I claim:

The ornamental design for a glass ashtray or similar article, substantially as shown and described.

T. CLARENCE HEISEY.
